GOLF PUTTER HEAD

Leo J. Ernst, Los Angeles, Calif.
(18640 Superior St., Northridge, Calif. 91324)

Filed Apr. 23, 1970, Ser. No. 22,600

Term of patent 14 years

Int. Cl. D21—02

U.S. Cl. D34—5

Fig. 1

Fig. 2

Fig. 3

Fig. 4

Fig. 5

Fig. 6

Fig. 7

FIG. 1 is a rear elevational view of a golf putter head showing my new design;

FIG. 2 is an end elevational view of the club design taken from the right of FIG. 1;

FIG. 3 is a front elevational view of the club design;

FIG. 4 is an end elevational view of the club design taken from the right of FIG. 3;

FIG. 5 is a plan view of the club design;

FIG. 6 is a bottom view of the club design; and

FIG. 7 is an end elevational view of an alternate club design identical in appearance with the earlier embodiment except that the shaft falls in the general plane of the club head.

I claim:

The ornamental design for a golf putter head, as shown and described.
